UNITED STATES PATENT OFFICE.

JUSTUS KOCH, OF PHILADELPHIA, PENNSYLVANIA.

DESIGN FOR A FABRIC FOR HANGINGS.

SPECIFICATION forming part of Design No. 28,481, dated April 19, 1898.

Application filed January 14, 1898. Serial No. 666,709. Term of patent 3½ years.

To all whom it may concern:

Be it known that I, JUSTUS KOCH, a citizen of the United States, residing at the city of Philadelphia, in the county of Philadelphia and State of Pennsylvania, have invented and produced a new and original Design for a Fabric for Hangings, of which the following is a specification, reference being had to the accompanying drawings, forming part hereof, to in which—

Figure 1 is a front view of a fabric embodying the particular features of design of my said invention. Fig. 2 is a rear elevational view of the fabric, and Fig. 3 is a longitudinal 15 central sectional view through the fabric on the lines *x-x* of Fig. 1.

The leading feature of my design consists in the unitary structure made the subject of illustration, having the shape or configuration shown.

Referring to the drawings, A represents the basket-like structure of the fabric provided with substantially square or block-like configurations *a*, consisting of a series of parallel vertically-arranged threads locked or tied by oppositely-disposed chain-stitch threads *b* at suitable distances apart and extending throughout the fabric, as illustrated in Figs. 25 1 and 2. Between the series of square or

block-like configurations *a*, in which certain of the threads thereof are continued to assume staggered relationship of said square or block-like configurations *a* of the fabric, the chain or lock-stitch threads *b* are continued longitudinally or crosswise of the fabric through 35 or across substantially square-shaped openings *d*. These threads *b* are of single twist or texture in appearance on the face, where they tie the series of vertically-arranged parallel threads constituting the square or block-like configurations *a* of the fabric, as illustrated in Fig. 1, while on the back and in the spaces or openings *d* these threads *b* are of a chain-stitch form, as clearly illustrated in Fig. 2 of the drawings.

Having thus described my invention, what I claim as new, and desire to secure by Letters Patent, is—

The design for a fabric for hangings, as herein described and illustrated.

In testimony whereof I have hereunto set my signature in the presence of two subscribing witnesses.

JUSTUS KOCH.
